UNITED STATES PATENT OFFICE.

LOUIS A. HOERR, OF ST. LOUIS, MISSOURI.

CAR-DOOR FASTENER.

SPECIFICATION forming part of Letters Patent No. 665,095, dated January 1, 1901.

Application filed October 30, 1899. Serial No. 735,147. (No model.)

To all whom it may concern:

Be it known that I, LOUIS A. HOERR, a citizen of the United States of America, residing at St. Louis, in the State of Missouri, have 5 invented a certain new and useful Car-Door Fastener, of which the following is such a full, clear, and exact description as will enable any one skilled in the art to which it appertains to make and use the same, reference being had to the accompanying drawings, forming part of this specification.

My invention relates more particularly to a car-door fastener to be used in connection with a car having a flush door—that is, a door 5 set into the side of the car, so as to be flush therewith.

The object of my invention is to provide a car-door fastener which while simple of construction and not liable to get out of order will firmly hold a flush door in its closed position.

My invention consists, primarily, in the combination, with a car-door fastener, of a member pivotally mounted on said fastener and 5 adapted to bear against the door and hold it in its closed position.

In the accompanying drawings, which illustrate a car-door fastener made in accordance with my invention, Figure 1 is a front elevation of the fastener and a portion of the side of the car to which the same is attached. Fig. 2 is a side view of the same, the side of the car and door being shown in section; and Fig. 3 is a top plan view also showing the side 5 of the car and door in section.

Like marks of reference refer to similar parts in the several views of the drawings.

5 is a portion of the side of a car, and 6 is a portion of a flush door set into the same.

My fastener consists of a base-plate 7, from which extends a sole 8, provided with an upwardly-extending lip 9. These parts are preferably provided with a strengthening web or rib 10. Extending upwardly from the base-plate 7 is a portion 11, which acts as a rub-knob to hold the door 6 out of contact with the side of the car while the said door is being moved back and forth. The fastener is held in position by means of a bolt 12 passing through the base-plate 7 and a bolt 13 passing through the rub-knob 11.

Pivoted to the lip 9 by means of a pin 15 is a substantially L-shaped member 16, which is provided with a curved end 17, adapted to

come in contact with the door 6. The member 16 is preferably provided with a strengthening web or rib 18. The member 16 is provided with seal-wire openings 19, and corresponding seal-wire openings 20 are formed in the sole 8 of the fastener. Through these seal-wire openings a seal-wire 21 may be passed and secured by a seal 22, so as to seal the member 16 to the fastener in position to hold the door closed.

In operation the member 16 of my fastener 65 is forced down into the position shown in full lines in Fig. 2 of the drawings, so that the curved end 17 will bear firmly against the door 6 and hold same in its closed position. The seal-wire 21 is then passed through the 70 openings 19 and 20 and secured by the seal 22. When it is desired to open the door 6, the seal 22 is removed and the part 16 drawn upwardly and allowed to fall in the position shown in the dotted lines in Fig. 2, when the 75 door can be operated in the usual manner.

It will be seen that my fastener is simple of construction and not liable to get out of order and at the same time that it will not only hold firmly the door in its closed position, but also enable it to be securely sealed.

I am aware that a car-door fastener has been heretofore used in combination with a wedge, which was pivotally mounted to the car-door, so as to swing in a plane parallel to said door, 85 and therefore I do not claim such construction.

Having fully described my invention, what I claim as new, and desire to secure by Letters Patent of the United States, is—

90 In a car-door fastener, the combination with a bracket provided with a sole and upturned lip and having at one side of said sole an upwardly-projecting securing and rub plate, of an arm pivoted to said lip at the opposite side 95 of said sole and adapted to bear against the face of the door, and means for securing said bracket to the side of the car above and below said pivoted arm, substantially as described.

100 In testimony whereof I have hereunto set my hand and affixed my seal in the presence of the two subscribing witnesses.

LOUIS A. HOERR. [L. S.]
